PROCESSING SUGAR

Jacob J. Neuman, South Salem, N. Y., assignor to
 United States Patent Development and Royalty
 Company, South Salem, N. Y., a company of
 New York

Original application March 24, 1939, Serial No.
 263,974. Divided and this application June 8,
 1939, Serial No. 277,989

2 Claims. (Cl. 127—64)

The present invention relates to improvements in apparatus and method for processing sugars and the like and relates more particularly to an improved apparatus and method for heating and conditioning sugar magmas and other sugar liquor mixed with crystal or granular sugar, as well as similar mixtures, which exist in various steps of the processing operations. This application is a division of my co-pending application Serial No. 263,974 filed March 24, 1939.

It has for its primary object the heating and mixing of the material during its transfer from one location to another and without appreciable collecting or adherence of the material to the heating surfaces.

In order to make the advantages of this new method of processing clearly understood, a brief description of the first few steps in the refining process of beet and cane sugar and the difficulties experienced with present methods will be given.

The raw sugar in crystal form is the initial condition of the sugar. Each crystal has a thin coating of molasses and other uncrystallizable matter, according to the completeness of the previous sugar making process complementary to the extraction of the sugar from the original cane or beets. It is the purpose of these primary processing steps, which are described below, to remove this coating of molasses and other syrups leaving the sugar crystals in as nearly a pure state as possible. The primary difficulty experienced consists in removing a maximum amount of said molasses and syrups without at the same time removing any of the sugar crystal itself. With present methods a considerable portion of the sugar crystal is dissolved along with the molasses and syrup and it is a primary object of my invention to obviate this condition.

In the present methods of separation, the raw sugar is mixed with an affination syrup (usually called greens, syrup or molasses) which also contains a considerable amount of uncrystallizable material. The result of this mixing is to coat the raw sugar crystals with this liquid making a heavy, sluggish mixture hereafter called magma. Obviously, this magma if kept fairly hot will have a much lower viscosity than otherwise, thus being easier to handle and separate. Therefore, heated affination syrup is used enabling the initial mixing to be accomplished more easily and requiring less greens to be used to attain the desired viscosity.

At present this heating is accomplished by raising the temperature of the affination syrup to about 180° to 190° F. and mixing it with cold

5 raw sugar in conveyor screws. The final temperature of the resulting mixture, hereafter referred to as magma, being about 120° to 130° F. Due to the fact that it is inherently impossible to introduce the hot affination syrup in such a manner that it will immediately contact all of the cold raw sugar, it is obvious that portions of the raw sugar are momentarily heated to temperatures approaching 180° F. when initially contacted by this hot syrup. This results in melting of the sugar crystals. The crystals so melted do not recrystallize when the mixture attains its final temperature of 120° to 130° F. and since the purpose of the centrifugal extractors 10 15 20 25 30 35 40 45 50 55

in which the magma is subsequently processed, is to separate the solid crystals from the liquids this melted sugar is separated from the solid crystals along with the affination syrup and can only be retrieved by several additional and costly processing steps.

With my invention this melting of the sugar crystals is entirely obviated since the affination syrup initially contacts the raw sugar in a cold condition or in any event at a temperature not exceeding the desired final magma temperature. The mixed affination syrup and raw sugar crystals are then brought up to the final temperature together and no part of the mixture ever attains a temperature in excess of this final temperature.

After the initial greens and raw sugar mixing, called affination, resulting in the magma, the latter is transferred to a large tank with sloping sides converging downward. In this tank are several longitudinal shafts rotating slowly. These shafts in turn bear paddles or blades which mix the magma constantly and keep it in a uniformly fluid condition always ready for the next processing step. This large tank, called the mixer, also serves as a storage place to take up variations in the rate of introduction of raw sugar and the rate of subsequent operations.

The next step in the process consists of centrifuging the magma, thus throwing off all liquids, even the denser ones. After the liquids are about all thrown off, a light spray of warm water is played on the sugar in the centrifugal device, thus rinsing off any remaining liquid and "washing" the sugar crystals. The whole step of centrifuging is called washing and the resulting product is called wash or washed sugar.

The washed sugar is now discharged from the centrifugal machine and falls into a screw conveyor or other suitable means to take it to the next step in the process. The machines, are

lined up in a row under and parallel to the big mixer and the conveyors receive the washed sugar from several centrifugals.

It is evident that the liquids thrown off from the centrifugals during spinning are rather cool and, hence sluggish to handle by ordinary pumping facilities. It is, therefore, desirable to heat these greens before pumping is attempted. This has been accomplished in the past by pumping the greens immediately through a closed heater, where they pass through copper tubes which, in turn, were surrounded by live steam. This made the greens hotter and more fluid, therefore easier to handle as well as putting them in the proper condition for making more magma since most of the greens thus heated is usually led back to the initial step of mixing the greens and raw sugar. However, the difficulty with this type of heater has been that the tubes quickly become clogged, due to the nature of the greens and require frequent cleaning.

The washed sugar is quite dry when plowed out of the centrifugal machine. In order to facilitate handling and at the same time prepare this washed sugar for subsequent steps in the refining process, it is mixed with water and heated by live steam in open heaters. The water used is usually "sweet water" resulting from the rinsing of various sugar tanks and machinery. It is clean water having dissolved in it a small amount of sugar. The utilization of this sweet water is very important, as there is no other way to efficiently reclaim the small amount of dissolved sugar. It is thus evident that the sweet water is abundant, being accumulated from many parts of the refinery. To boil it away to reclaim the sugar is an expensive process due to costs of steam, equipment and labor.

Also, due to the undesirability of superfluous water in any sugar liquors on account of added evaporating being thereby necessary, it is the practice to keep the density of the resulting sugar liquor as high as can be conveniently handled. Sugar liquors of relatively high densities are most easily handled by the pumps and filters when kept at temperatures a little below boiling. Efficient methods are always desirable to maintain the temperature approximately constant without adding steam, as the steam condensing on contact with the liquor adds this condensate to the liquor, thus decreasing the density. The maintenance cost of conventional heating equipment to perform this task is high due to the slow accumulation of solid matter on the heat transfer surfaces congealing due to excessive local temperature, which tends to burn or caramelize the sugar of the liquor. The collected deposits must be cleaned off periodically not only to keep the equipment in efficient operation but to keep all old or stale material out of the various parts to comply with sanitary standards which must be met in the various food industries.

It is thus seen that at several steps in the process it is necessary to heat the material being processed and that, at present, this heating is variously accomplished by the use of live steam in open heaters and by stationary coils in closed heaters and is attendant with many difficulties.

It is, therefore, a primary object of this invention to provide a heating means designed to overcome these difficulties namely: dilution of liquors due to condensed steam, clogging of heaters due to caramelization of sugar on coils and

melting of the sugar crystals due to the uneven heating.

It is also a further object of the invention to provide a system where the heating medium is utilized in the various steps in such a manner that a maximum portion of its original heat energy is utilized.

Another important object is to permit utilization of the surplus sweet water, previously mentioned, in the dilution of the liquors or mixtures, instead of the present practice of using the condensate from the live steam used in the open heaters or so-called melters.

In addition, there are other objectives such as the elimination of separate heating steps: for the "greens" used in the initial preparation of the magma; for the washed sugar liquor before pumping away to the next step of the refining process; and for the greens as thrown off from the centrifugal extractors. Other objects of the invention will be evident in the following description of the raw sugar treatment as carried on with this invention incorporated in the various steps of the process.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a vertical sectional view taken through an apparatus constructed according to the present invention.

Figure 2 is an enlarged longitudinal sectional view taken through a shaft and its connections and showing an improved arrangement of packing.

Figure 2^a is a view similar to Figure 2 showing a slight modification.

Figure 3 is a side elevation of a half section of conveyor or screw flight showing one method of formation of the same.

Figure 4 is an edge view taken from the inner edge of said flight.

Figure 5 is a cross-section taken through one of the flights and showing a method of attachment to the shaft and to a reinforcing and bearing band.

Figure 6 is an end view of a form of hollow paddle employed.

Figure 7 is a side view of the same, and

Figure 8 is an enlarged fragmentary side view of the raw sugar melting screw with parts broken away and parts shown in section.

Referring more particularly to Figure 1, 1 designates generally a raw sugar mingler or the trough constituting the same which is supplied with the raw sugar 2 by conveyor 3 from a suitable source of supply.

In the trough 1 is a spiral or screw conveyor driven by the electric or other motor 4 through appropriate transmission connections, the screw being rotated in such a sense or direction that it will advance the material in the trough 1 toward the left where the same will flow over the baffle 5 and be delivered to the tank 6 which is designated as the magma mixer. In this tank is a spiral conveyor or screw 7 rotated by a motor 8 through the connections indicated for the purpose of advancing the material to the spouts 10 by which the same is delivered to the centrifugal extractors 9. Sweet water is delivered to the extractors by the connection 11 from the source of supply or header 12.

The separated sugar from the extractors 9 is delivered to the trough 15 of the raw sugar melting screw 17 to which sweet water is admitted by a pipe 16 from the header 12. The screw 17 rotates in a direction or sense to move the material toward the right along the bottom 20 of the trough toward the weir or baffle wall 18. The screw 17 is rotated by electric or other motor 19 through appropriate gearing or connections.

The heavier matter or "greens" from the extractors 9 is delivered down the inclined runway 21 to the end of an enclosed trough 22 in which rotates the greens screw 27 for advancing the greens to the greens tank 23. Pump 26 pumps the fluid out of the greens tank 23 to a header 25 and to a pipe 24 which conveys the liquid to the raw sugar mingler 1. A screen 28 is preferably interposed between the greens screw trough 22 and the greens tank 23.

Steam from a header or other steam source 20 31 is supplied by pipe connections 32, 32^a and 32^b to the steam pump 26, to the hollow shaft of the hollow screw 17 and to the hollow shaft of the hollow screw 27.

A steam pipe 35 connects the opposite ends of the shaft of the greens screw 27 with one end of the hollow shaft of the magma mixer hollow screw 1, the other end of this screw 1 being connected with a pipe 33 which conveys the steam to one end of the hollow shaft of the raw sugar mingler 1. The other end of the hollow shaft of mingler 1 being connected to an exhaust header 34.

The end of the hollow melting screw 17 communicates with condenser chamber 66 connected by pipe 11 with a steam trap 69 also connecting with pipe 33.

Discharge end of hollow melting screw 17 projects through and has a bearing upon disc 70 mounted upon the shaft of the screw 17. The disc 70 has a broad rim 68 rotating in flanged guide 67 carried by the casing of the condenser chamber 66.

At the right hand end of melting screw trough 17 and below greens tank 23 is the raw sugar liquor tank 42 disposed to receive the liquor which is caused to overflow baffle 18 by the action of screw 17. A screen 41 guards the entrance to the raw sugar liquor tank 42 from which, by means of a pump 43, the raw sugar liquor is delivered to the header or destination.

Referring more particularly to Figure 2, a fragmentary end portion of a hollow shaft 51 is shown which shaft might be the shaft of any one of the screws. For example, shaft 51 is denominated the shaft of the conveyor 1. The wall of the magma mixer through which the shaft passes is designated at 50. At the outer open end of shaft 51 is secured by appropriate fastenings 75 a disc 52 through which loosely passes the nipple 53. In Figure 1 this nipple 53 is shown as coupled to an elbow 76 by which connection is made to the flexible hose or other pipe 35. Gaskets 54 extend about the nipple 53 on opposite sides of the disc 52. A coil spring 55 surrounds the nipple 53 within the protection of the end of the hollow shaft 51 and bears at one end against the inner of the gaskets 54 urging such gasket 54 yieldingly up against the inside face of disc 52. At its other end the coil spring tends to expand against a ring 56 which engages one of two or more packing rings 57. The coil spring 55 in effect expands the packing rings 57 between the rings 56 and 58, the latter

being affixed upon the inner end portion of the nipple 53.

Inside of the tank wall 58, a sleeve 59 of greater diameter than the external diameter of shaft 51 surrounds a portion of the shaft and may be affixed at one end to wall 58. At its other end the sleeve carries a disc 77 held in place by appropriate fastenings 78. Packing rings 79 in any suitable numbers are interposed between disc 77 and the follower ring 80 against which presses at one end a coil spring 81 abutting at its other end against wall 58.

Compression of the packing rings causes the same to expand radially. The rings 57 positioned between nipple 53 and the internal annular wall of hollow shaft 51; while the packing rings 79 expanding between the shaft 51 and the sleeve 59 prevent leakage from the magma mixer about the shaft out through the opening from which protrudes the end of the hollow shaft 51. The nipple 53, communicating as it does with the steam supply pipe 35, leads steam or hot vapor into the end of hollow shaft 51 and the packing 57 prevents this steam from leaking out around the exterior of the nipple 53. These packing rings 57, positioned as shown and described remote from the disc 52 and gaskets 54, enable a loose fit of the nipple 53 to take care of conditions of variation in correct alignment.

This Figure 2 therefore shows one method of making a fluid path connection to an end of the rotating screw shaft 51. The gaskets or collars 54 are tightly fitted on the pipe nipple 53. The pipe nipple 53 is positively held in position against a longitudinal or axial motion by the disc 52 and collars 54. The packing 57 always being compressed by the spring 55 maintains a tight joint between the moving or rotating hollow shaft wall 51 and the stationary pipe nipple 53.

Referring more particularly to Figures 3 and 4, there is here shown one form of flight of which the various screws may be made. These figures show a 180° section of the flight as made in one piece of cast steel. The edges 82 and 83 are bevelled to permit good welds to be made when being fabricated on the hollow shaft, for instance the hollow shaft 51 of Figure 2. Similar pieces may also be easily made from flat plates warped to the shape shown and welded together at the vertex of the V. This vertex is designated at 84. Also similar cast plates may be made with ears, such as the ears 85, shown in Figure 5, provided to fit against the shaft, such as the shaft 51, whereby bolts, screws or other fastenings may be employed instead of welding the flights to the hollow shaft. Ears might also be provided for joining of adjacent sections of the flights when installing whereby bolts could be used throughout and welding on the job eliminated. Such an installation would simplify replacement of one or more sections of hollow flight when necessary without resorting to the burning and welding which would otherwise be necessary in the case of flights fabricated by welding.

Referring more particularly to Figure 5, I have here shown a sectional view of a flight unit 61 which is the central flight unit, for instance of the raw sugar mingler 1. The hollow flight 61 is cast or built up by welding, or otherwise, with bracket 62 on the peak of the V. Suitable holes, either threaded or drilled through, are provided for the fastening in place of the cylindrical collar 63 by the fastenings 64. This collar 63 is of a diameter slightly larger than the screw

86 in the raw sugar mingler 1, and is of a suitable low friction metal so that when engaged in a cooperating part 87 of the stationary trough 1 of the mingler, such for instance as the flanged member 67 of Figure 1, the collar 68 provides suitable support for the screw shaft assembly 5 against eccentric displacement due to possible localized resistance of the screw flights to turning. By using a large diameter hollow shaft and with the flights thereon to support this shaft in the manner of a truss, it is not likely that an intermediate bearing for the rotating part will be necessary in the installation.

Referring more particularly to Figures 6 and 7, these figures show a complete unit of a paddle-type beater element 87' which it is desirable to use in the case of thick magmas and the like to increase the turbulence. Units of this type would ordinarily be installed between adjacent turns of the hollow V-type element by welding to the shaft as shown in Figure 1 in connection with the mingler conveyor 1. Such shaft has openings about which the paddle elements 87' are welded or otherwise secured whereby there is communication between the hollow shaft and the hollow paddles 87' for the free flow of the heating medium. Whenever no longitudinal movement of the substance being heated is desired the paddle type of heater 87' might be used exclusively.

In operation, the sugar from the storage bins or bag dump (not shown) is conveyed by the conveyor 3 to the raw sugar mingler 1. Hot water flows upwardly through pipe 33 and into the left hand end of the hollow shaft of the mingler screw 86. This hot water circulates through the hollow flights 86 and through the hollow paddles 87' and passes out into the low temperature water line 34. It will be noted that the hot water flows in a direction from left to right through the hollow shaft and hollow screw 86 which thus becomes a heating element and also a screw conveyor; while the sugar material 2 is advanced by the spiral conveyor or screw from right to left. The counterflow principle herein applied permits the mixed magma flowing over the baffle 5 to have become heated to nearly the temperature of the water supplied to the heating element or screw and its shaft.

Suitable consistency of greens is supplied to the mingler through the line 24 from the greens pump 26 when there is a sufficient quantity being pumped; otherwise from the main greens header 25, such as when starting operations. This greens will of course have a temperature according to that of the greens header 25, except as reduced by temperature drop in the long connecting pipe line 24.

The raw sugar and greens having been thoroughly mixed in the raw sugar mingler 1 by the action of the conveyor 86, and also by the paddles 87' if used, the resulting magma is discharged over the end baffle 5, falling into the mixer 6. Here the heated screw conveyor 7 rotates slowly, keeping the mixture in a proper condition. It is necessary to maintain this mixing motion at all times, as two or three hours without mixing would permit the magma to become sluggish or almost set, and the mixer screw could not be started up again.

This conveyor 7 receives its heating water through the pipe line 35 from the greens screw 27 and the flights of the conveyor 7 are also preferably hollow.

From time to time the magma is drawn off into

the centrifugal extractors 9 through the spouts 10. Here the magma is centrifuged, the fluid portion being thrown off and drained away in the trough 21. Also during the spinning a small amount of sweet water is sprayed upon the whirling magma by suitable spray nozzles 11. This spray water also is forced off completing the washing of the sugar, after which the machine is slowed down and the washed sugar plowed out through the bottom openings 14 into the raw sugar melting screw trough 15.

The raw sugar melting screw 17 turns fairly rapidly and mixes the washed sugar from the centrifugal extractors with sweet water from the main sweet water header 12 flowing into the screw 17 by means of pipe 16. The heated screw conveyor 17 is heated by steam entering at the discharging end being fed in through the pipe 32* from the steam header 31. The steam flows into the heater element flight 17, where it completely condenses in heating up the raw sugar and sweet water mixture being agitated together in the raw sugar melting screw trough 15; the screw tending to move the mixture toward the discharge end baffle 18.

The raw sugar, properly washed and discharged into the raw sugar melting screw trough 15, mixes with a suitable amount of sweet water supplied from the pipe 16 to form a smoothly running liquor by the time it has been worked along the trough 20 by the heated screw conveyor 17. The sweet water supplied is adjusted to insure complete dissolving of the sugar before it leaves the melting screw trough 15 over the baffle 18. This raw sugar liquor then passes through the screen 41 to the raw sugar liquor tank 42, from which it is pumped to the refinery raw sugar liquor line 44 by the centrifugal pump 43.

It will be observed that the counterflow principle operates in the melting screw trough 15, the steam entering at the position of discharge of the melted sugar, thereby giving the raw sugar liquor a temperature only a few degrees below that of the entering steam at the discharge end of conveyor 17. As the steam condenses and cools it gives up heat along its path of travel in the flight of screw 17 allowing a large amount of heat to be absorbed by the raw sugar melting into the sweet water.

The screw installation for the raw sugar melting screw 17 has incorporated in it if desired the special type of flight shown in detail in Figures 3 and 4.

The left end of the screw 17 opens directly into chamber 66 where such end is fitted through the disc 70 which seals the trough compartment 15 from the chamber 66. The cylindrical bearing strip 68 which rotates with the heater element screw assembly 17 may be firmly attached thereto by suitable bolts or cap screws which allow replacement as might be needed. The chamber 66 is thus completely sealed off from the main trough compartment 15 by means of the end disc 70, the bearing strip 68 mounted on the rotating part 17 and the cooperating stationary part 67 mounted in the frame of the main trough 15 at the left end thereof. The closed chamber 66 drains by means of the connecting pipe 71 into the steam trap 69 which will pass water from the chamber 70 66 into the hot water pipe 33 but will not allow any steam to pass into this pipe 33 from the chamber 66.

During the operation of the raw sugar melting screw 17, the steam entering the hollow shaft by means of the pipe 32* from the steam header

31 passes into the heater element flight 17 through the holes 72. The plug 73 in the hollow shaft prevents the passage of steam any further within this shaft. The steam flows through the entire flight 17 of the rotating heater element or screw, losing heat to the raw sugar and water mixture within the trough 15 and condensing within the hollow flight 17. The steam pressure forces this condensate along and out of the open end of the flight 17 to the chamber 66 together with some occluded and live steam which failed to condense. The condensate collects in the bottom of the chamber 66 and is forced out through the steam trap 69. When an excess of steam collects within the chamber 66, the pressure built up will retard the flow of additional steam into the hollow flight 17 from the steam header 31. This will permit more complete condensation of the existing steam within the flight 17 until the pressure in the chamber 66 is again reduced to lower value which will permit more live steam to enter. This is a suitable governor for the regulation for the steam entering the moving or rotating heater element 17 and is desirable to prevent waste of steam and overheating of the raw sugar liquor.

The use of this method of providing a path for fluid flowing from the moving heater element flight 17 to the external stationary pipe installation also provides an alternative installation method, eliminating the packing gland of Figure 2 at this end of the hollow shaft. At the same time it provides a bearing for the moving element to rotate upon, which in some instances would be a distinct advantage in providing additional shaft support.

The greens, namely the liquid portion of the magma thrown off by the centrifugal extractors 9 and the spray water used in the said extractors 9, drain away in the trough 21, collecting in the greens screw 22. Here the greens absorb heat from the heated screw conveyor 27 which is heated by steam flowing from the steam main 31 through the pipe 32 and 32^b into the heater element flight at the discharge end of the greens screw 22. As explained in the case of the raw sugar melting screw 17, the counterflow principle operates to bring the greens up to a suitable temperature by bringing about a large amount of heat transfer to the latter.

The greens flows from the discharge end of the greens screw 22 through the screen 28 into the greens tank 23, from which it is pumped into the main greens header 25 by the steam pump 26, except that a sufficient amount of the greens is led through the pipe 24 back to the raw sugar mingler to take part in the affination process there.

It is to be understood that the heating fluid, usually steam or hot water, could be circulated in different ways. Thus, in the winter, steam might be introduced directly to the magma mixer 6 and the raw sugar mingler 1 to keep the temperature high enough. Also instead of heating the various screw heater elements from the plant steam header, hot condensate from various other equipment might be utilized; thus adding to the thermal efficiency of the system. Possibly the greens heating screw 22 would be constructed using a long moving heater element screw conveyor rotating in a large diameter pipe to insure thorough mixing and keep the entire heating surface almost totally immersed in the greens. The drawing shows a short section thus arranged.

Sometimes it is found desirable to add sweet

water to the greens in order to decrease the density to allow proper fluidity to permit pumping and the like. Under the conditions of combined uses it might be desirable to heat the sweet water supply.

In Figure 2^a the packing rings 78 are disposed against the wall 50 instead of against the disc 77 and the position of the follower ring 80 and the spring 81 is reversed accordingly.

In Figure 8 a portion of the shaft 51^a of the raw sugar melting screw 17 is shown to more clearly illustrate the internal plug 73 and the holes or perforations 72 which admit the steam into the hollow flight 17.

It will be understood from the foregoing that the condensate from the steam in any or all of the hollow screws or conveyors does not contact the sugar crystals or the magma and therefore this condensate does not have the effect to dilute the melted sugar. For this reason it is possible with this steam to use more sweet water for the purpose of bringing the sugar liquor to proper density. The utilization of as much sweet water as possible at this point in the process is very important since there is no other way to efficiently reclaim the sugar dissolved therein. Consequently the hollow conveyor, preventing contact between the steam, or its water of condensation, and the sugar or mixture thereof with the "greens" or affination syrup, is very important as not creating further sweet water and in fact as achieving a recovery of the sugar dissolved in the sweet water in other less efficient parts of the plant.

It is obvious that various changes and modifications may be made in the details of construction and design of the above specifically described embodiment of this invention without departing from the spirit thereof, such changes and modifications being restricted only by the scope of the following claims.

What is claimed is:

1. In the processing of sugar which consists in adding an affination syrup to raw sugar crystals in a mingling zone to form a magma, agitating and mixing the magma in a mixing zone, centrifuging the magma to separate sugar crystals from greens, melting the centrifuged sugar crystals in a melting zone in the presence of sweet water, collecting the separated greens in a storage zone, and returning said greens to the mingling zone as the affination syrup for admixture with raw sugar crystals; the method of heating the materials in the said several zones to respectively different temperatures, which consists in conducting a heating fluid in a stream through the melting zone in indirect contact with the sweet water and sugar crystals of the centrifuge in said zone to maintain a melting temperature of the sugar crystals, simultaneously conducting a second stream of heating fluid through the greens storage zone in indirect contact with the greens in the said zone to reduce the viscosity of the greens before returning said greens to the mingling zone as affination syrup, conducting one of said streams of heating fluid through the magma mixing zone in indirect contact with the magma in said mixing zone to reduce the viscosity of the magma which is being agitated, combining the first-named stream with the second-named stream of heating fluid in a single stream at the resulting mean temperature, and conducting the combined stream through the mingling zone in indirect contact with the raw sugar and affination syrup in said zone, to maintain a

temperature in the latter below the temperature in the magma mixing zone, whereby all of said zones are subjected to heat without dilution of the materials by said heat other than such of the materials themselves.

2. In the processing of sugar which consists in adding an affination syrup to raw sugar crystals in a mingling zone to form a magma, agitating and mixing the magma in a mixing zone, centrifuging the magma to separate sugar crystals from greens, melting the centrifuged sugar crystals in a melting zone in the presence of sweet water, collecting the separated greens in a storage zone, and returning said greens to the mingling zone as the affination syrup for admixture 15 with raw sugar crystals; the method of heating the materials in the said several zones to respectively different temperatures, which consists in conducting a heating fluid in a stream through the melting zone in indirect contact with the sweet water and sugar crystals in said zone to maintain a melting temperature of the sugar crystals of the centrifuge in the latter, simulta-

neously conducting a second stream of heating fluid through the greens storage zone in indirect contact with the greens in said zone to reduce the viscosity of the greens before reducing the greens to the mingling zone as affination syrup, 10 conducting said second-named stream of heating fluid through the magma mixing zone in indirect contact with the magma while being agitated in said mixing zone to reduce viscosity of the magma, and then conducting the same stream in indirect contact with the sugar crystals and affination syrup of the mingling zone, and combining said first-named stream with said second-named stream of heating fluid before the latter enters the mingling zone to obtain a resulting mean temperature, to maintain a temperature in the latter below the temperature in the magma mixing zone whereby all of the zones are subjected to indirect heating without dilution of the materials by said heat other than such dilution of the materials themselves.

JACOB J. NEUMAN.
